ELECTRIC CONTROL DEVICE

Philip Sitzer, Irvington, N. J., assignor to Tung-Sol Electric Inc., Newark, N. J., a corporation of Delaware

Application May 18, 1949, Serial No. 93,909

4 Claims. (Cl. 200—88)

1

This invention relates to electric control devices.

In one aspect of the invention it relates to electric circuit control devices of the combined electromagnetic and thermal type disclosed in United States Schmidinger Patents Nos. 2,103,276 and 2,103,277, for "Flasher Device," issued December 28, 1937.

One object of the invention is a new and improved electric control device of the above character in which the life of the switch contacts is materially increased, and in which there is a material reduction in manufacturing costs.

Another object of the invention is a new and improved relay structure for flasher and other purposes having more uniform operating characteristics over long periods of time, and improved uniformity in operation of switches produced in quantity.

Another object of the invention is a new and improved electromagnetic control device enabling a wide degree of control to be exercised over the operating characteristics in production, and which will retain such characteristics over relatively long periods of time.

Another object of the invention is to provide means for suppressing objectionable vibratory action on flasher and other similar switches, and especially in switches of the plug-in type.

Another object of the invention is a new and improved thermally-operated flasher.

Still another object is to provide a new and improved electric control device.

These and other objects will become more apparent from the following description and accompanying drawings forming part of this application. In the drawings:

Fig. 1 is a front elevation of a switch in accordance with the invention, with a portion of the housing removed to expose the operating portions;

Fig. 2 is a side elevation of the embodiment illustrated in Fig. 1;

Fig. 3 is a front elevation of another embodiment of the invention with a portion of the outer housing removed to expose the operating parts thereof; and

Fig. 4 is another embodiment of the invention.

In the manufacture of electric control devices of the above character, considerable difficulty has been experienced, to my knowledge, both in the assembly thereof as well as in the adjustment to obtain devices having substantially uniform operating characteristics. The adjustment of the device was critical and did not in many instances retain the adjusted characteristics when put into service.

With my invention I have been able to overcome these difficulties and produce a very much more stable and easily controlled switch, having

2

substantially uniform characteristics throughout its life. I have also been able to materially extend the life of the switches, eliminate objectionable vibratory action, and materially reduce the costs of the switch in mass production.

Figs. 1 and 2 of the drawings illustrate one form of a flasher switch embodying my invention. In the figures, 10 denotes the outer casing of the switch which is mounted on a base 12 of insulating material and secured to the casing by a U-shaped portion 14 swaged or otherwise formed on the bottom of the casing 10 and engaging the periphery of the insulating base 12.

The switch is provided with an electromagnetic core 16 having enlarged end portions 18 and 20, more clearly indicated in Fig. 1, and a relatively narrow central portion 22 about which a coil of wire 24 is formed. The core 16 is held in an upright position within the housing 10 by means of an L-shaped bracket 26 having one leg 28 fastened to the base by a pair of lugs 30 extending from the terminal 32 through suitable openings in the base, and bent inwardly over the leg 28 to clamp it tightly to the base 12.

The lugs 30 may also engage suitable recesses in the sides of the leg 28 to provide a more secure and rigid mounting for the bracket 26. The upstanding leg 34 of the bracket 26 may be spot-welded or otherwise suitably fastened to the lower part 20 of the core to hold it in the upright position.

Formed integrally with the L-shaped bracket 26 is a lug 36 extending outwardly and inclined upwardly relative to the base. This lug is provided with an opening 38 for the purpose of holding one end of an expansible-contractible pull wire 40.

This embodiment of the invention is provided with a single elongated armature 42 bridging the ends 18 and 20 of a core 16 and terminating in its upper end in an L-shaped or offset portion 44 to which the upper end of the pull wire 40 is attached by welding or other similar means. To prevent kinking or damaging of the pull wire at the upper end of the armature, the offset portion 44 is formed with a rounded part 46 over which the wire passes. The wire 40 is stretched between the offset part of the armature 44 and the bracket 36 to hold the armature in the open position illustrated in Fig. 1. The lower end of the pull wire 40 is insulated from the bracket 36 by means of a small spherical bead of glass 48 molded about the pull wire and adapted to be partially received by the opening 38 in the bracket 36 so that the pull wire 40 can pass through the opening without touching the metal edges thereof. The lower end of the armature 42 is fixedly mounted to the core 16 by means of a spring 50 generally of Z-shape, having its lower leg 54 welded or otherwise fastened to the vertical edge or surface 53 of a re-

cess or cut-out 56 in the lower core part 20. The upper leg 52 of the spring 50 forms substantially an L with the transverse portion of the spring, and is welded or otherwise fastened to the lower end of the armature 42.

With the armature 42 mounted in this manner, it is movable angularly to open and close a pair of contacts 58 and 58', the latter of which is formed on the armature. In addition to the angular movement, the armature is also movable longitudinally under the influence of the pull wire 40 which is mounted at an acute angle to the armature and spaced therefrom so that upon contraction of the pull wire it will exert a small lateral force on the armature tending to open the contacts, and a rather large longitudinal force in a downward direction tending to slide the contacts one upon the other in the opening operation. The contact 58 is supported by an L-shaped bracket member 60 which is formed integrally with a rectangular washer-shaped member 62 held between insulating washers 70 and 70' and clamped to the upper section 18 of the core by means of a through rivet 72. The bracket member 74, also held in place by the rivet 72, has an L-shaped lug 76 extending therefrom, and passes in a transverse direction in the rear of the armature to limit the outward travel thereof.

The electric circuit controlled by this device may include a source of electrical energy and a device, such as an incandescent lamp, as the load, connected in series with the terminals 32 and 32' of the switch. The switch circuit consists of the terminal 32 which is connected by means of the L-shaped bracket 26 and the lower core part 20 to the armature supporting member 50, thence through the armature 42 to contacts 58 and 58', and the coil 24 to the terminal 32'. The pull wire 40 is connected at one end to the armature 42 and at the other end to the contact 58 by means of a coiled wire 78.

In the operation of the switch, the connection to the load circuit is completed through the pull wire 40 and the ballast wire 78, which are effectively connected across the normally open contacts 58 and 58'. The resistance of the pull wire and ballast 40 and 78, respectively, impedes the flow of current to the load and limits it to a relatively small value, insufficient to operate the load. When the load includes or comprises one or more incandescent lamps, this current is insufficient to illuminate the lamps, but will, however, heat the pull wire and permit it to expand. The armature mounting spring 50 will pull the armature 42 inwardly to close the contacts and energize the load. At the same time, the electromagnet coil 24 is also fully energized and exerts a magnetic pull on the armature to assist in holding the contacts together. At this point the pull wire is short circuited by reason of the closure of the contacts 58 and 58', whereupon the pull wire starts to cool. During the cooling of the pull wire, contraction takes place, which exerts a continuously increasing force on the armature, a portion of which is in the outward direction tending to open the contacts while the remaining and somewhat larger portion is in the direction of the armature tending to slide the contacts one over the other during the opening operation. This action is accomplished by reason of the new and improved armature mounting which constantly cleans the contacts and greatly lengthens their life. Moreover, a pronounced snap action opening is obtained which further adds to the life of the contacts. This snap action results because

at the instant of the opening of the contacts, when the pulling force of the pull wire is just able to overcome the holding force of the electromagnet, there is a collapse of the magnetic field constituting the primary holding force on the armature.

In Fig. 3, I have illustrated another form of a flasher switch having two armatures. In this form, I have also included a new and improved means for overcoming objectionable vibration of the switch, which further materially improves the operation as well as lengthening its life.

This form of the invention is similar in certain respects to the embodiment illustrated in Figs. 1 and 2, and therefore like numbers have been used to denote similar parts in each embodiment. In each of the embodiments, the armature mounting bracket 50 biases the armature to the normally closed position of the contacts 58 and 58', and particularly good results have been had with a bracket formed of "Z-nickel," which is a product of the International Nickel Company and consists of approximately 98% nickel with other alloying elements, although other resilient materials (such as spring steel, tempered coppers, and brasses) may also be used.

To dampen vibration of the armature 42, a spring 80 of tempered steel or other suitable material is welded or otherwise fastened at one end to the lug 76 which extends transversely of the armature 42. The spring depends upon said lug and contacts the armature 42 at a point substantially below the center thereof and tends to bias the armature to the closed position. However, the force exerted by this spring is not sufficient of itself to close the contacts 58 and 58' but supplements the biasing force produced by the Z-shaped armature mounting bracket 50. The spring 80 mounted in this manner effectively dampens the vibration of the relatively rigid armature 42 which is preferably formed of annealed, cold rolled steel, which can be produced with uniform and stable magnetic properties.

As pointed out above, the embodiment in Fig. 3 includes a second armature 82 which is fastened to the lower end portion 20 of the magnet core 16 by means of a piece of spring metal 84 which is welded at one end to the base of the armature 82 and at the other end to the left-hand edge of the core part 20. This spring is preferably formed to provide no bias either inwardly or outwardly on the armature 82. A second spring 88 providing an outward bias is fastened to the base of the armature and extends upwardly to contact an outwardly depending lug 90 formed as an integral part of the bracket 74 and extending transversely of the armature 82. A second lug 92, also formed integrally with the bracket member 74, is disposed parallel to the member 90 and passes behind the armature 82 to limit the outward movement thereof when the magnet core 24 is de-energized by the opening of the contacts 58 and 58' associated with the armature 42. The contact 86 is carried by and electrically connected to the armature 82, while the contact 86' is supported by a bracket member 94 insulated from the magnet core 16 but supported thereby by means of the rivet 72 in substantially the same manner as the lug or bracket member 60 is supported in Fig. 2. The bracket member 94 carrying the contact 86' is electrically connected by the lead 96 to a downwardly depending lug member 98 fastened to the insulating base 12. The lug 100 shown in full view in Fig. 3 supports the L-shaped bracket member 26 in the same man-

ner as described in connection with lug 32 in Fig. 1. Immediately behind the lug 100 is a second similar lug 102 which is the equivalent of lug 32' in Fig. 1, and has an outstanding lug member 104 to which one end 106 of the coil 24 is attached. Through suitable connections to the lugs 98 and 102, the contacts 88 and 88' may be used to break a separate or auxiliary circuit, and the contacts 58 and 58' may be used for effecting the flashing operation only, or, if desired, to operate a load in substantially the same manner as described in connection with Fig. 1.

With this new and improved structure for switches or flashers, such as the thermal switch described, it has been found that far greater control can be exercised over the operating characteristics in the production and manufacture of the device, and that a switch, once adjusted to the desired characteristics, will retain them for extended periods of time. Moreover, by reason of the particular method of mounting the armatures, a sidewise welding operation can be effected in place of vertical and difficult welding operations which were used, to my knowledge, in prior practice. These factors materially reduce the cost of production, and in addition produce greatly improved switches. Moreover, the particular arrangement of the mounting of the armature 42 provides good wiping contact during the opening operation and this, coupled with the snap-action opening effected by the particular arrangement and direction of the forces applied to the armature to open it, greatly improves the life of the contacts; while the suppressor spring 80 greatly reduces objectionable vibration of the armature and produces more stable and uniform operation of the switch as a whole.

In Fig. 4 I have illustrated another embodiment of the invention, having a single armature. This embodiment is similar to the embodiment illustrated in Figs. 1 and 2, and like numerals have been applied to like parts in each of these embodiments. In Fig. 4, however, I have illustrated a bracket member 74' which is of somewhat different shape than the bracket illustrated at 74 in Fig. 1, in that it is provided with but a single outstanding lug member 76 partially embracing the armature 42.

What is claimed is:

1. An electric circuit control device having an electromagnet and an armature, comprising an electromagnetic core having a recess at one end with one edge substantially parallel to the armature when in attracted position, a Z-shaped spring having one leg disposed parallel to said edge and secured thereto and its opposite and parallel leg secured flush to one end of said armature, the middle leg of said spring forming an angle of less than 90° with each of the other legs, the depth of said recess and the length of the middle leg of said spring being correlated to bring the supported end of said armature close to the core above the recess therein.

2. A pull wire thermal switch comprising an electromagnet, a pair of contacts, an armature actuated by the magnet and responsive to energization of the magnet to close the contacts, a pull wire having one end attached to and spaced from the free end of the armature and operable upon cooling in opposition to the magnetic pull of the magnet to open the contacts and exert the major component of its force along the length of the armature, means for mounting the other end of said armature for angular and longitudinal move-

ment including a Z-shaped bracket member, said member tending to bias the armature to the closed position, and spring means on said armature engaging a fixed abutment for supplementing the biasing effect of the Z-shaped member.

3. A thermal switch comprising an electromagnet, a pair of armatures associated with said magnet, and a pair of contacts individual to each armature and adapted to be opened and closed by movement of their respective armatures in response to energizing and de-energizing of said electromagnet, a thermally responsive pull wire having one of its ends fixedly mounted with respect to said magnet and the other of its ends connected to one of said armatures to open the armature upon contraction of the pull wire against the force of the magnet, means for mounting said one armature including a Z-shaped spring yieldable under the action of the pull wire on said armature to permit angular and longitudinal movement of the armature, said spring biasing the armature to a closed position of its associated contacts, a suppressor spring fixedly supported with respect to the magnet at a point near the free end of said one armature and extending along the length of said armature to contact it at a point near its other end, and biasing the armature to supplement the bias effected by said mounting spring, means for mounting the second armature including a yieldable spring, and a second spring associated with said second armature and adapted to bias it to a normally open position of its associated contacts.

4. In an electric switch, an electromagnet, at least one armature responsive to said magnet, mounting means for said armature comprising a Z-shaped spring with the ends of the spring being in spaced alignment and in alignment with the armature, one end of said spring being fixedly mounted and the other end fastened to the armature, said spring biasing the armature toward attracted position, means connected to the other end of said armature for moving the armature away from attracted position against the bias of said spring under certain conditions, and a suppressor spring strip fixedly supported with respect to the electromagnet at a point near the free end of said armature and extending along the length of said armature and contacting it at a point near said mounting means to bias the armature in a direction to supplement the bias effected by said Z-spring.
